PRESS CONTROL SYSTEM

Walter Ernst, Mount Gilead, Ohio, assignor, by
mesne assignments, to The Hydraulic Press
Corporation, Inc., Wilmington, Del., a corpo-
ration of Delaware

Application November 28, 1934, Serial No. 755,245

4 Claims. (Cl. 60—52)

This invention relates to pressure-exerting machinery and, in particular, to systems for the control of presses.

One object of my invention is to provide a pressure-responsive system for the reversal of a press when a predetermined position of the platen has been reached, this system being applicable to presses of any type whether mechanical or hydraulic.

Another object is to provide a press control system wherein the pressure exerted by the press is caused to operate an electrical control circuit to reverse the press when a predetermined position of the platen has been reached.

Another object is to provide an electro-mechanical system for the control of presses wherein the pressure exerted by the platen is caused to vary the current supplied to the control circuit, and this in turn is caused to operate the reversal devices.

Another object is to provide a press control system wherein the press platen is caused to compress a material whose current-carrying ability varies under pressure, such as a pile of carbon plates, this variation of pressure and the consequent variation of current being caused to operate relay devices which in turn actuate the reversal mechanism of the press.

Another object is to provide an arrangement for reversing a press when a predetermined position of the platen has been reached, wherein the pressure exerted by the platen is caused to vary the current-carrying capacity of an electrical circuit, and this in turn is caused to operate a "trigger action" relay, such as a vacuum tube of the "thyatron" or "grid glow" type, the operation of the relay causing the actuation of the press reversal means, such as a reversing valve.

In the drawings:

Figure 1 is a diagrammatic front elevation of a press, partly in section, showing the principal mechanical elements in one embodiment of my press control system as applied to a hydraulic press;

Figure 2 is an electrical wiring diagram showing the connections of the various electrical elements in the press control system shown in Figure 1.

Figure 3 is a view of a portion of the circuit of Figure 1, showing a modified construction wherein a solenoid is caused to operate the shift ring of a variable delivery pump.

Referring to the drawings in detail, Figure 1 shows a press consisting of a base 10, a top piece 11, and strain rods 12 interconnecting the top

and base members. The top piece 11 is provided with a hydraulic cylinder 13 having a piston head 14 and piston rod 15. The latter is connected to the press platen 16 which reciprocates vertically between the guide plates 17 attached to the sides of the press. The base 10 is provided with an anvil-like portion 18 for receiving the work or dies by which the operation of the press is accomplished.

The platen 16 is provided with an extension 19 secured thereto and having a portion 20 adapted to engage a pile of material, such as the carbon plates 21, whose current-carrying ability varies under pressure. A base 22 supports the carbon pile 21 against the thrust of the platen 16 arm 19. The electrical connections of the carbon pile 21 will be described later.

The hydraulic circuit for operating the press consists of a pump 25 of any suitable type, and having a pressure line 26 and a suction line 27. The latter withdraws oil from the tank 28. From the tank 28, a discharge line 29 runs to a reversing valve 30, and conducts fluid from the ports 31 and 32 at the opposite ends thereof.

The reversing valve 30 is provided with a valve rod 33 having the spaced heads 34 and 35. A port 36 serves to admit pressure from the pressure line 26 of the pump, whereas a port 37 is connected to the working or forward line 38 communicating with the space above the piston head 30 in the hydraulic cylinder 13.

From a port 39, the return line 40 runs to the space below the piston head 14 in the hydraulic cylinder 13. In the return line 40 is the high pressure relief valve 41. From the relief valve 41, the pipe 42 communicates with the discharge line 29 running to the tank 28. The high pressure relief valve 41 is adapted to discharge fluid into the discharge line 29 and tank 28 when the pressure in the line 40 exceeds a predetermined amount. The working or forward line 38 similarly contains a high pressure relief valve 43 having a discharge line 44 communicating with the tank 28 to discharge fluid when the pressure in the line exceeds a predetermined amount. These relief valves 41 and 43 may be of any suitable type.

The valve rod 33 having the piston heads 34 and 35 is connected to the armature 45 of a solenoid 46. The valve rod 33 is urged in the opposite direction to the pull of the solenoid 46 by the coil spring 47 engaging the collar 48, and urging the valve in a righthand direction.

The electrical circuit for the control of the press is shown in Figure 2. Current is supplied

from the power lines 50 and 51 to the primary winding 52 of a transformer 53. The transformer 53 is provided with suitable secondary windings 54, 55, and 56. From the secondary winding 55, the line 57 runs to one terminal of the current-varying unit or carbon pile 21. From the opposite terminal of the carbon pile 21, the line 58 runs to the grid 59 of the vacuum tube 60 by way of the resistor 61. Between the line 62 running from the opposite terminal of the transformer secondary 55 and the line 58 is arranged the capacitor 63. The line 62 continues to the negative pole of the battery or other current source 64, the opposite or positive terminal of which is connected by the lines 65 and 66 to the electrode 67 of the vacuum tube 60. The electrode 67 is heated by the filament 68, current being supplied for this purpose by the lines 69 and 70 running from the transformer secondary 56.

The lines 65 and 66 are connected by the line 71 to the negative terminal of the battery or other source of current 72. From the positive terminal of the latter, the line 73 runs to one terminal of the operating coil 74 of the normally-closed electro-magnetic switch 75, having the armature 76. The opposite terminal of the operating coil 74 is connected by the line 77 to the plate 78 of the vacuum tube 60. A spring 79 urges the switch bar 75 into a normally-closed position.

One terminal of the transformer secondary 54 is connected by the line 80 to the manual switch 81 and thence by the line 82 to the upper switch bar 83 of the normally-open contactor switch 84. The line 85 runs to the lower switch bar 86 thereof. The switch bars 83 and 86 of the contactor switch 84 are urged into normally-open positions by the spring 87.

The fixed terminal of the electro-magnetic switch bar 75 and of the upper contactor switch bar 83 are interconnected by the line 88. From the fixed terminal of the lower contactor switch bar 86, the line 89 runs to one terminal of the solenoid 46, from the opposite terminal of which the line 90 runs to the transformer secondary winding 54. From the latter the line 91 runs to the operating coil 92 of the contactor switch 84, and from the opposite side thereof, the line 93 runs to one terminal of the manual switch 81; whence the line 94 runs to the electro-magnetic switch bar 75. The contactor switch 84 is provided with an armature 95, engaging the switch bars 83 and 86, and actuated by the operating coil 92 in the manner described below.

In operation, the press is started by closing the manual switch 81, which is preferably of the push button variety. Current from the transformer secondary 54 is then caused to energize the operating coil 92 of the contactor switch 84 by way of the line 80, switch 81, and lines 93 and 91. The consequent closing of the switch bar 83 against the urge of the spring 87 causes the operating coil 92 to be henceforth energized when the switch 81 is released. The holding circuit thereof includes the lines 80 and 82, the switch bar 83, the line 88, the normally-closed switch bar 75, and the lines 94, 93 and 91 to the transformer secondary 54. The closing of the lower switch bar 86 causes the winding of the solenoid 46 to be likewise energized from the transformer secondary 54 through the lines 88, 82, and 85, the switch bar 86, and the lines 89 and 90.

The energization of the solenoid 46 causes its armature 45 and the valve rod 33 to be shifted to the left, causing the valve heads 34 and 35 to be

moved into the dotted positions shown in Figure 1, against the urge of the coil spring 47. Pressure fluid now passes from the pump 25 and the pressure line 26 through the middle chamber of the valve 30, out the port 37 and through the working line 38 to the chamber above the piston head 14, causing the latter to move down, together with the platen 16. The fluid discharged from the chamber beneath the piston head 14 passes through the return line 40, and the port 39 into the righthand end chamber of the valve 30, thence through the port 32 into the discharge line 29 running to the tank 28. The relief valves 41 and 43 serve to constantly pass the fluid therethrough and do not influence the operation of the circuit except when an excessive pressure develops.

As the platen moves downward and engages the work, its arm 19 compresses the carbon pile 21, causing its electrical resistance to be decreased. As this occurs, current is permitted to flow therethrough in increasing amounts from the transformer secondary 55, by way of the lines 57 and 58, changing the potential of the grid 59 in the vacuum tube 60.

The vacuum tube 60 is preferably of the so-called "thyatron" or "grid glow" type, wherein a substantially constant voltage drop exists between the cathode 67 and the anode or plate 78. The potential of the grid 59 is kept negative by the battery 64. When the potential of the grid 59, however, exceeds a predetermined amount, the vacuum tube 60 suddenly becomes operative, causing the electron flow to conduct current through the circuit represented by the lines 73 and 77, the operating coil 74 of the contactor switch 75, the battery 72, the lines 71 and 66, the cathode 67 and plate 78.

The vacuum tube 60 thus acts, in effect, like a relay which is operative only when the current supplied to the grid thereof exceeds the "firing potential" of the tube. The "trigger action" of the tube 60 is not operative until the current passed by the carbon pile 21 attains a sufficient magnitude through the lowering of the resistance thereof by the compression of the carbon pile.

The energization, in this manner, of the operating coil 74 of the electromagnetic switch 75 lifts the armature 76 and the switch bar thereof, opening the circuit between the lines 94 and 88 against the urge of the spring 79. This breaks the holding circuit of the contactor switch coil 92, causing the latter to become de-energized and the switch bars 83 and 86 thereof to be opened by the urge of the spring 87. The opening of the switch bar 86 breaks the circuit between the lines 85 and 89, and consequently de-energizes the windings of the solenoid 46, permitting the valve rod 33 to be urged to its righthand position under the influence of the coil spring 47.

Under the urge of the spring 47, the valve heads 34 and 35 take the righthand positions, as shown by the solid lines in Figure 1. Under these circumstances, pressure fluid flows from the pressure line 26 of the pump 25 through the middle chamber of the valve 30 and the line 40 and the relief valve 41 into the space beneath the piston head 14, causing the latter to rise and the platen 16 to be retracted. The fluid in the space above the piston head 14 returns to the tank 28 by way of the line 38, the relief valve 43, the port 37, the lefthand end chamber of the valve 30, the port 31 and the discharge line 29.

The platen 16 moves upward until it reaches

the top of its stroke, where it may be halted by any suitable means. In the arrangement shown, the relief valve 41 will then cause the pressure fluid to be discharged through the line 42 into the tank 28 by way of the discharge line 29.

As the platen 16 nears the top of its stroke, it may be caused to operate a positionally responsive switch 98, breaking the circuit in the line 71, and consequently de-energizing the plate circuit of the vacuum tube 60. Some arrangement of this sort is advisable, since the "thyatron" or "grid glow" tubes have the peculiarity of starting operation when the grid potential exceeds the "firing potential" but of not stopping when the grid potential subsequently falls below the "firing potential". The opening of the switch 98 by the platen 16 at the top of its stroke de-energizes the coil 74 of the electromagnetic switch 75 and allows its switch bar to be returned to its normally-closed position under the influence of the coil spring 79.

To re-start the press for another working stroke, the switch button 81 is again depressed, and the foregoing cycle of operations repeats itself. As the platen passes downward, however, it releases the positionally-responsive switch 98, thus again closing the circuit in the line 71 and placing the plate circuit again in condition for operation. It will be understood, however, that if alternating current is utilized in place of the direct current from the direct current source 72 to energize the plate circuit, the operation of the tube 60 may be interrupted by the phase change thereof.

It will be understood that instead of the reversing valve 30 and the constant delivery pump 25, a variable delivery pump having its fluid lines 126 and 127 connected respectively to the forward and return lines 38 and 40 may be used and the flow thereof varied by suitable electrical means responsive to the action of the electrical circuit described above. For example, in Figure 3, the armature 45 of the solenoid 46 is operatively connected to the flow-varying or shifting ring 101 of a variable delivery pump 100, and the subsequent shifting thereof brought about by the operation of the solenoid 46 is thus caused to reverse the flow of the fluid in the pipe lines 38 and 40 without the necessity for employing the reversing valve 30. For the purpose of compensating for the unequal supply of fluid required on opposite sides of the piston head 14, due to the space occupied by the piston rod 15, a compensating valve 102 is arranged between the pipes 38 and 40 with its end chambers connected thereto. Its middle chamber is connected to the line 27' from the fluid tank 28, and its valve element 103 automatically moves to and fro to permit fluid to be drawn from the tank 28 into the space below the piston head 14, or to be discharged from the space above it. The details of the compensating valve 102 form no part of the present invention, and will be found fully disclosed in the United States Patent No. 1,653,350, granted on December 20, 1927 to Walter Ernst.

It will be understood that I desire to comprehend within my invention such modifications as may be necessary to adapt it to varying conditions and uses.

Having thus fully described my invention, what I claim as new and desire to secure by Letters Patent is:

1. In combination, a hydraulic press having a reversibly movable plunger, a pump, fluid-reversing means for reversibly distributing the pressure

fluid from said pump to said plunger, an electrically-controlled shifting element for shifting said fluid-reversing means, a current-varying instrumentality responsive to the application of pressure for varying the electric current passing therethrough, means associated with said plunger for simultaneously transmitting pressure to a work-piece and said instrumentality upon operation of said plunger, and an electrical device operatively responsive to the reception of a predetermined current from said current-varying instrumentality to change the electrical condition of said electrically-controlled shifting element and thereby bring about the shifting of said fluid-reversing means.

2. In combination, a hydraulic press having a reversibly movable plunger, a pump, fluid-reversing means for reversibly distributing the pressure fluid from said pump to said plunger, an electrically-controlled shifting element for shifting said fluid-reversing means, a current-varying instrumentality responsive to the application of pressure for varying the electric current passing therethrough, means associated with said plunger for simultaneously transmitting pressure to a work-piece and said instrumentality upon operation of said plunger, and a vacuum tube relay operatively responsive to the reception of a predetermined current from said current-varying instrumentality to change the electrical condition of said electrically-controlled shifting element and thereby bring about the shifting of said fluid-reversing means.

3. In combination, a hydraulic press having a reversibly movable plunger, a pump, fluid-reversing means for reversibly distributing the pressure fluid from said pump to said plunger, an electrically-controlled shifting element for shifting said fluid-reversing means, a current-varying instrumentality responsive to the application of pressure for varying the electric current passing therethrough, means associated with said plunger for simultaneously transmitting pressure to a work-piece and said instrumentality upon operation of said plunger, and an electrical device operatively responsive to the reception of a predetermined current from said current-varying instrumentality to change the electrical condition of said electrically-controlled shifting element and thereby bring about the shifting of said fluid-reversing means, said current-varying instrumentality comprising a pile of carbon elements.

4. In combination, a hydraulic press having a reversibly movable plunger, a pump, fluid-reversing means for reversibly distributing the pressure fluid from said pump to said plunger, an electrically-controlled shifting element for shifting said fluid-reversing means, a current-varying instrumentality responsive to the application of pressure for varying the electric current passing therethrough, means associated with said plunger for simultaneously transmitting pressure to a work-piece and said instrumentality upon operation of said plunger, and an electrical device operatively responsive to the reception of a predetermined current from said current-varying instrumentality to change the electrical condition of said electrically-controlled shifting element and thereby bring about the shifting of said fluid-reversing means, said fluid-reversing means comprising a valve and said shifting element comprising a solenoid adapted when energized to shift said valve.
